UNITED STATES PATENT OFFICE.

MARK ST. CLAIR ELLIS, OF THE UNITED STATES NAVY.

SANITARY FINGER-MOISTENER.

1,035,827.

Specification of Letters Patent. Patented Aug. 13, 1912.

Application filed April 27, 1912. Serial No. 693,661.

To all whom it may concern:

Be it known that I, MARK ST. CLAIR ELLIS, lieutenant commander, United States Navy, a citizen of the United States, residing at Mare Island, in the county of Solano and State of California, have invented a new and useful Sanitary Finger-Moistener, of which the following is a specification.

My invention relates to improvements in finger moisteners, and the particular object is to make the same sanitary and more sightly in appearance than the ordinary desk sponge cup.

I attain these objects by the mechanism illustrated in the accompanying drawing, in which—

Figure 1 is an assembly drawing showing the device attached to an ordinary commercial glass sponge cup; Fig. 2 is a detailed drawing of the perforated metal diaphragm.

Similar letters refer to similar parts throughout the several views.

Referring to the drawing, D is a metal diaphragm stamped out to fit the top of the sponge cup, having perforations therein to admit moisture therethrough; B is a sponge cup; W represents the water therein; and S is a wetted sponge contained in the cup; P is a felt pad placed over the sponge with

its ends dipping in the water. This pad, by capillary action, draws up the water and keeps the top of the sponge moistened. The diaphragm, D is placed on top of the pad and is retained in the cup by the lugs, L.

The action of the device is as follows: When water is placed in the cup the sponge and the felt are moistened, and by pressing upon the diaphragm, D, a small amount of moisture is caused to pass to the outside of the diaphragm, D. This moisture may be transferred to the finger in the ordinary manner by touching it.

Having thus described my invention and the method of its use, what I claim as new and desire to secure by Letters Patent of the United States, is—

A finger moistener of the type described, consisting of a cup, a sponge, a felt pad, and a perforated diaphragm; said perforated diaphragm having lugs shaped to fit on the inside of said cup, and which when said diaphragm is pressed, it admits moisture to its surface through the perforations, substantially as shown and described.

MARK ST. CLAIR ELLIS.
